UNITED STATES PATENT OFFICE

2,688,252

PSYCHROMETER WITH AIR CIRCULATING
MEANS

James F. King, Jr., Winston-Salem, N. C., assignor to The Bahnson Company, Winston-Salem, N. C., a corporation of North Carolina

Application September 22, 1950, Serial No. 186,293

4 Claims. (Cl. 73—338)

1

This invention relates to motorized psychrometers and more particularly to psychrometers including wet and dry bulb thermometers over which an air stream is established by a fan or blower.

Objects of the invention are to provide a motorized psychrometer in the general form of an elongated rod or tube supporting a wet bulb and a dry bulb thermometer, batteries, and a miniature motor and fan for establishing an air current over the thermometers, and an adjustable computer for determining the relative humidity from the observed wet and dry bulb temperatures. An object is to provide a psychrometer of the type stated which includes a signal system for displaying a significant signal when the batteries are of low voltage and should be replaced.

These and other objects and the advantages of the invention will be apparent from the following specification when taken with the accompanying drawings in which:

Fig. 1 is a side elevation of a motorized psychrometer embodying the invention;

Fig. 2 is a top plan view of the same;

Fig. 3 is a fragmentary central vertical section on a larger scale and showing the motor and fan assembly separated from the supporting structure;

Fig. 4 is a transverse vertical section on line 4—4 of Fig. 1;

Fig. 5 is a transverse vertical section on line 5—5 of Fig. 3;

Fig. 6 is a transverse vertical section on line 6—6 of Fig. 1; and

Fig. 7 is a fragmentary central vertical section through the outer end of the psychrometer.

In the drawings, the reference numeral 1 identifies the tubular rear end or handle portion of an elongated support which is preferably formed by cutting approximately semi-cylindrical sections from a stainless steel tube. A relatively short section is removed from the intermediate portion of the tube to leave a semi-cylindrical section 2 to which a complementary semi-cylindrical plate 3 is detachably secured, as will be explained later, and a longer section is removed from the opposite side of the outer end of the tube to leave an outer section 4 of somewhat more than semi-cylindrical form which is spaced from the section 3 by a short section 5 of full cylindrical form. In general, the functions of the several parts of the elongated support are as follows: the tubular rear portion 1 constitutes a handle for carrying the psychrometer and holding it in spaces where humidity measure-

2

ments are to be made, and also serves as a container for a battery of dry cells; the intermediate section 2 and the complementary plate 3 form a housing for a miniature electric motor and fan which are mounted on the plate 3; the outer section 4 provides the support for wet and dry bulb thermometers; and the section 5 constitutes a yoke within which the thermometer bulbs are located in the path of the air stream established by the fan.

A removable cap 6 closes the rear end of the handle portion 1 and carries a spring 7 which engages the zinc can electrode of the adjacent dry cell 8 of a battery, preferably three cells of conventional "flashlight" type, within the handle portion 1 which is of a diameter to be conveniently grasped in the hand in the same manner as a flashlight. An insulating disk 9 is secured across the forward end of the tubular portion 1 of the support, and a conductive pin 10 extends axially through the disk for engagement by the center contact of the forward dry cell 8 and a cooperating spring contact 11 of the motor-fan assembly supported upon the plate 3.

25 This assembly includes a switch 12 having one terminal to which the spring contact 11 is secured, and a second terminal from which leads 13, 14 extend in parallel to a miniature electric motor 15 and to one terminal of a lamp socket 16 in which a signal lamp 17 is seated. The other side of the motor is grounded upon the support by a lead 18, and the second terminal of the lamp socket 16 has a contact strip 19 soldered thereto for cooperation with a grounded spring contact 20 which is normally biased away from the contact 19, but is forced into contact with it by a centrifugal governor 21 on the motor shaft when the battery voltage drops below that value which affords stable motor operation for a pre-selected time interval, say 30 seconds, sufficient to bring the wet and dry bulb thermometers to stable minimum readings. A red glass lens or bullseye 22 is mounted in an opening in the part 2 to afford a clear indication to the operator when the motor speed drops below a preselected value due to depletion of the battery of dry cells 8.

35 The motor 15 has a snug fit within a mounting ring 23 which is secured to the plate 3 by screws 24, and a fan or centrifugal blower 25 is mounted upon the outer end of the motor shaft. A series of exhaust openings 26 are provided in the support section 2 and the mounting plate 3, and a pair of slots 26' are provided in the section 2 to establish an air stream for cooling the motor. The plate 3 and its assembly are detachably

secured to the support section 2 by screws 27 which are threaded into the ring 23.

The wet bulb thermometer W and the dry bulb thermometer D are mounted upon a sub-base of generally cruciform cross-section comprising a strip 28 which, for convenience of description, will be termed the vertical strip, and a pair of horizontal strips 29, 29 which are welded to the opposite sides of strips 28 below the center line thereof. The thermometers are mounted upon the respective strips 29 by clips 30, and the strips 29 terminate short of the thermometer bulb to avoid interference with the air flow around the bulbs. The lower portion of the strip 28 is notched, well in advance of the thermometer bulbs, to receive the water tank 31 which is welded or soldered to the lower faces of the strips 29. The lower surface of the water tank is curved to fit snugly against the adjacent wall of the support section 4, and the tank filler cap 32 extends through an opening in that wall to close the filler opening and also to lock the sub-base securely to the support. A linen wick 33 on the bulb of the thermometer W passes into the tank through a rubber bushing 34 which is tightly compressed upon the wick to prevent leakage from the tank. The rearward end of the vertical plate 28 fits snugly within the support section 5 when the sub-base is slipped into the outer support section 4, and a cap 35 is welded to the outer end of the sub-base to seat upon the outer end of section 4 with a snug fit.

At least the rear portion of the metal sub-base which is exposed to the air stream is covered or coated with heat insulating material, indicated by the stippling 36, and the interior of the support section is also lined with insulating material 37 to reduce heat transfer from the supporting structure to the thermometer bulbs.

A computer or rotary slide rule for determining relative humidity from the observed wet and dry bulb temperatures is mounted upon the outer portion of the handle section 1. The computer comprises a ring 38 press-fitted upon the handle 1 and marked with graduations W' of wet bulb temperature, a ring 39 rotatable on the handle section and carrying a scale D' of dry bulb temperatures at the edge adjacent the fixed ring 38 and a scale RH of relative humidity at its opposite edge, and a second fixed ring 40 carrying a fiducial mark 41 for cooperation with the relative humidity scale.

The psychrometer will usually be held in horizontal or approximately horizontal position when the relative humidity of the air in the zone or space is to be determined, but other angular arrangements of the psychrometer are equally effective when the zone or space is limited and it is not convenient to employ the horizontal arrangement. The motor should operate for a sufficient period, according to the time-response characteristics of the thermometers, to obtain stable minimum readings. The computer ring 39 is then adjusted to aline the observed readings on the adjacent scales of the rings 38 and 39, and the relative humidity value appears on scale RH opposite the mark 41.

The accuracy of the determination of relative humidity depends of course upon the accuracy of the measurement of the wet and dry bulb temperatures. Air flow should be maintained for a preselected minimum period, and at a preselected minimum velocity, to obtain accurate temperature readings. The velocity of the air streams varies with the motor speed, and this

varies with the battery voltage. The centrifugal governor 21 and switch 19, 20 afford a positive indication or warning when the battery voltage drops to such value that the motor 15 can not drive the fan 25 at such speed as to establish the desired minimum air flow velocity over the thermometer bulbs.

It is to be understood that the invention is not limited to the particular embodiment herein illustrated and described since various modifications in the shape, size and relative arrangements of the component parts fall within the spirit and scope of the invention as set forth in the following claims.

I claim:

1. In a motorized psychrometer, an elongated support comprising a tubular handle portion of a diameter to be conveniently grasped in the hand and an outer section in axial alignment with and having a transverse cross-section of the order of that of the handle portion, a wet and a dry bulb thermometer mounted on the outer section of said support and parallel to the axis thereof, and power means for establishing an air stream moving inwardly along said outer section of said support upon which said thermometers are mounted; said power means comprising batteries within said tubular handle portion, an electrical motor and fan at the outer end of said hollow handle portion of said support, and an assembly comprising a sub-base supporting said thermometers and a water reservoir, and means detachably securing said assembly to said outer section of said elongated support; the bulb ends of said thermometers being located adjacent the inlet side of and in the air stream established by said fan.

2. In a motorized psychrometer, the invention as recited in claim 1, wherein a tubular section of said support extends over the bulb ends of said thermometers to form a passage for the air stream established by said fan.

3. In a motorized psychrometer, the invention as recited in claim 2, in combination with means on said sub-base to provide separate air passages over said wet bulb and said dry bulb thermometers.

4. In a motorized psychrometer, the invention as recited in claim 1, wherein said outer section of said elongated support is an approximately semi-cylindrical extension of said tubular handle portion, in combination with a sub-base of generally cruciform cross-section formed by metal strips at right angles, said sub-base being seated in said outer section of said support; said sub-base including a water reservoir, and said thermometers being mounted on said sub-base at opposite sides of a strip of said sub-base.
